UNITED STATES PATENT OFFICE.

HENRY B. LEAK, OF CHATHAM, ONTARIO, CANADA.

NECK-YOKE.

SPECIFICATION forming part of Letters Patent No. 364,266, dated June 7, 1887.

Application filed January 27, 1887. Serial No. 225,644. (No model.)

To all whom it may concern:

Be it known that I, HENRY B. LEAK, a subject of the Queen of Great Britain, residing at Chatham, in the Province of Ontario and Dominion of Canada, have invented certain new and useful Improvements in Neck-Yokes; and I do hereby declare that the following is a full, clear, and exact description of the invention, which will enable others skilled in the art to which it appertains to make and use the same.

This invention relates to neck-yokes; and its object is to provide a simple and improved yoke-ring which shall possess advantages in point of inexpensiveness, durability, and general efficiency.

In the drawings, Figure 1 is a perspective view of a neck-yoke embodying my improvements. Fig. 2 is a cross-section of the same. Fig. 3 is a transverse cross-section taken through the ring. Fig. 4 is a detail perspective view of the plate.

Corresponding parts in the figures are denoted by the same letters of reference.

Referring to the drawings, A designates the bar or yoke, which may be of any suitable construction, provided at its center with a circumferential grooved portion, a, forming shoulders a'.

B designates the yoke-ring, which comprises a single plate formed of annealed or soft steel, (thus insuring strength and flexibility,) and bent up to form a retaining eye or loop, C, and a top and bottom wing, D E, respectively. The loop C is formed at the center of the spring-plate, and is sprung over the grooved portion a and retained in position thereon by the shoulders a'. The top and bottom wings, D E, are formed of the end portions of the spring-plate and project forwardly from the front edges of the central loop. The wings of the plate are provided with the usual central eye or perforation, d e, respectively, and have their outer edges of circular form, preferably approximating a heart shape, as illustrated in the drawings. By thus forming the ring-plate of

a single plate of annealed or soft steel bent up as described, cheapness in manufacture is effected and great durability and strength secured.

F designates the leather, which is secured between the wings D E, and has its outer edge, f, extending to and corresponding with the contour of the outer edge of the wings of the plate. The inner edge, f², of the leather is extended, and projects from the inner edge of the wings of the plate to prevent the plate from contact with the pole. In the manufacture of my improved neck-yoke I prefer to use Spanish sole or harness leather, as may be best adapted, and the leather is provided with the usual central eye, f'. The leather is secured in position and the plates retained together by means of an annular series of screws, G, passing through perforations g in one of the plates and through corresponding perforations, g', in the leather, and entering screw threaded or tapped perforations g² in the other wing. It is obvious that in lieu of these screws rivets may be employed, as illustrated at H, Fig. 3.

I claim as my invention—

The herein-described improved yoke-ring bent up in a single piece from a spring-plate of annealed or soft steel and adapted to be sprung over the yoke, said spring-plate comprising integrally a central loop and the flat top and bottom wings projecting from the front edges of the loop and provided with the circumferential series of registering perforations, the leather filling projecting to the outer edges of the wings of the plate and having the projecting inner edge, f², and the annular series of securing-screws, substantially as and for the purpose set forth.

In testimony whereof I affix my signature in presence of two witnesses.

HENRY B. LEAK.
